BOHUMIL POLÁK, OF PRAHA-KARLIN, CZECHOSLOVAKIA

DEVICE FOR OPENING CONTAINERS, BOXES, TINS, OR THE LIKE

Application filed November 23, 1926, Serial No. 150,311, and in Czechoslovakia April 28, 1926.

This invention concerns improvements in or relating to devices for opening containers, boxes, tins or the like.

Openers having the shape of a lever or an eccentric and provided with a grip bent up at right angles are known. This construction, however, necessitates the use of massive materials. The opener according to the present invention is formed from thin sheet metal and has a peripheral groove whereby it is in engagement with the cover of the container so that it cannot fail to function and the opening operation can be effected by rotating it in the one or other direction.

Practical embodiments of the invention are illustrated by way of example in the accompanying drawings in which:—

Fig. 1 is a front elevation of one embodiment,

Fig. 2 a section on the line 2—2 in Fig. 1,
Fig. 3 a section on the line 3—3 in Fig. 1,
Fig. 4 an elevation of a second embodiment,
Fig. 5 a section on the line 5—5 in Fig. 4,
Fig. 6 a section on the line 6—6 in Fig. 4.

Referring to the drawings the openers illustrated in Figs. 1-6 each consist of a comparatively long strip a' of sheet metal with a raised centre portion which is of circular (b Figs. 1-3) or approximately elliptical (b' Figs. 4-6) shape and is provided with an opening to accommodate a hollow rivet c for the purpose of securing the opener to the lower portion d of the container.

According to the invention the opener is made from thin sheet metal and is provided with a pressed out peripheral groove f around the entire circumference of the raised middle portion b or b' . The opener engages with the edge of the cover e of the container by means of said groove. Strengthening edges g are formed at each end of the opener, this replacing the usual grips bent outwards at right angles.

The construction described enables the opener to be secured to the container in a novel

manner. A small flat surface extending to the edge only of the closed cover is pressed up in the lower part of the container when the same is perforated so that the tightness of the cover is as perfect as that of containers not provided with an opener. This advantage is most important since with the types of opener known hitherto the tightness of the container was impaired by the pressing of various grooves or recesses at parts of the container which should be tightly closed so that the contents quickly dried up and lost its quality. In known constructions in which the container is not pressed out to receive the opener, covers were used hitherto which had an edge extended by a stiffening flange whereby the container is made considerably more expensive and the tightness thereof impaired since the cover loses elasticity due to the flange and becomes loose.

In the third embodiment (Figs. 7-9) cylindrical raised portions h which are connected together by hollow pressed up longitudinal ribs i connected in turn by similar cross ribs j are pressed out at the two ends of the sheet metal member a^2 . The peripheral groove f is disposed partly in the raised portions h and partly in the longitudinal ribs i .

In the fourth embodiment (Figs. 10-12) a closed oval hollow rib h is pressed in an eccentrically pivoted oval sheet metal member a^3 and a peripheral groove f in the said rib. The member a^3 has a stepped extension a^4 , of which the centre portion l is raised to serve as a grip.

The hole for the connecting rivet c is preferably stiffened by bending the material twice whereby breaking of the edge thereof by the rivet is prevented.

Having now particularly described and ascertained the nature of my said invention and in what manner the same is to be performed, I declare that what I claim is:

In combination a receptacle having a lid telescoping thereupon, the telescoping sides

of said receptacle and lid forming an uninterrupted tightly contacting sealing zone of uniform width, the side of said receptacle being formed with a slight depression the bounds of which do not encroach upon said sealing zone, a cam device pivoted in the area of said depression at such point that it lies normally wholly below the edge of said lid, the lid engaging portion of said cam device comprising a grooved flange, the trough of whose groove is adapted to embrace the free edge of said lid adjacent said depression.

In testimony whereof I affix my signature.

BOHUMIL PÓLÁK.
